UNITED STATES PATENT OFFICE.

JACOB L. MARTIN, OF LEO, INDIANA.

WASHING-MACHINE.

SPECIFICATION forming part of Letters Patent No. 391,543, dated October 23, 1888.

Application filed October 19, 1887. Serial No. 252,813. (No model.)

To all whom it may concern:

Be it known that I, JACOB L. MARTIN, of Leo, in the county of Allen and State of Indiana, have invented a new and Improved 5 Washing-Machine, of which the following is a full, clear, and exact description.

The object of the present invention is to improve the construction of washing-machines of that class in which one wash-board is reciprocated with its face on or in proximity with the face of another wash-board for the purposes of securing durability and easy operation of the machine and for maintaining the articles to be washed to the action of the wash-boards; and 15 it consists in the construction and combination of various parts of the machine, all as will be hereinafter more fully described, and pointed out in the claims.

Reference is to be had to the accompanying 20 drawings, forming a part of this specification, in which similar letters of reference indicate corresponding parts in all the figures.

Figure 1 is a perspective view of the washing-machine, parts being broken away, Fig. 2 25 being a vertical cross-sectional view thereof on line *x x* of Fig. 1, and Fig. 3 a horizontal sectional view on line *y y*, Fig. 2, with the moving parts shown in all the views as in positions to separate the wash-boards from each other.

30 In the drawings, A represents the tub-body or receptacle of suitable shape and depth, having upwardly-inclining rest-boards B extending outwardly from the edge of the tub.

The rubbing or wash boards C C², with corrugated or other suitable form of operating-surfaces, are arranged for a reciprocating motion of the one in relation to the other, the board C² is arranged for adjustment as to its vertical position nearer or farther from the 35 center of the tub, and when adjusted runs always in the same vertical plane, and the opposing board C is arranged to be quickly and easily moved toward and against or away from the board C², and the constructions whereby 40 these capabilities are secured will be now described. Each wash-board C C², on its rear side, is provided with a rib or tongue, *a*, sliding in vertical openings or ways *b* in its respective carrying board or frame D or D², each 45 of which carrying-boards rests upon the bottom of the tub, their inward movements being

guided at their lower ends by the extended horizontal foot *d* on the carrying-board D, resting on the bottom of the tub and projecting through a recessed cleat, *d*², secured on the 55 receptacle body, and recesses *d*³ on board D², the board D about midway of its height having an outward horizontal arm, E, playing through and between horizontally-arranged guide-bars F, and a lever-arm, G, by one end, 60 *f*, pivoted to the end of the tub, passing the length thereof at its side outside of the carrying-arm, said arm at its intermediate portion, *f*², being pivoted to one end of a link, *f*³, which, by its other end, *f*⁴, is pivoted to the horizontal 65 arm E, affording easy means for the inward and outward projection of the carrying-board D, and the carrying-board D² is provided with a pair of horizontal arms, E² E³, playing through openings *g*² at the ends of a horizontal 70 cleat, *g*, said arms being provided with vertical holes *g*³, arranged in lines parallel with their length and in line with a vertical hole, *g*⁴, in each end of said cleat *g*, through which pins *g*⁵ pass, then holding the horizontal arms 75 and carrier-frame D² firmly in place.

Bearing in and supported by an arch-frame, H, is a horizontal crank-shaft, K, with crank-arms *h* *h*², provided with a winch-handle, *h*³, for turning it, and between the crank-arms *h* 80 *h*² and the rear tongues, *a a*, of the wash-boards are links or connecting-rods *k k*², their engagement with the crank-shafts by their upper ends being through their pivotal hanging, as at *j j*², to blocks *l l*², rotatably hung upon the 85 cranks *h* *h*², and by their other ends, *h*⁴, by being pivotally secured to swiveling blocks *m m*², pivoted, as at *n n*², to the tongues *a* of the wash-boards, the forming of such connections between crank-arms and wash-boards permitting 90 the free operation and movements of the wash-boards from and by the cranks in whatever positions they may be placed, as will be clearly understood.

Friction-rollers *p p* are hung by pintles in 95 slots *q q* of the carrier-frames D D² in a manner that their peripheries project beyond the front faces of said frames, forming anti-frictional bearings for the reciprocating movements of the wash-boards thereon, said wash-boards being held to bearing upon said rollers by the cross-pins *r r* passing through and 100

projecting at each side of their rear ribs, *a*, and bearing against the rear sides of the carrying-boards *D D'*, as shown.

An open-work flexible netting, *L*, is horizontally hung between the wash-boards by the side strips, *s*, being fastened to the carrying-boards *D D'*, and as said boards are moved together to bring the wash-board faces together for operation the middle portion of the netting 10 drops or folds downwardly; but on placing said boards apart from each other the said netting is drawn more or less taut and horizontal, bringing up the clothing to easy access and out of the bottom of the tub, where the dirtiest 15 portions of the water remain, and in a washing-machine such as hereinbefore described the vertically, reciprocating wash-boards will not crowd the articles being washed to any point in the machine beyond the plane of action 20 of said boards.

Having thus described my invention, what I claim as new, and desire to secure by Letters Patent, is—

1. In a washing-machine, the combination, 25 with the tub or receptacle and a crank-shaft supported above the same, of laterally-adjustable wash-boards, blocks pivotally connected to the said shaft and wash-boards, and links pivoted to the said blocks, substantially as described, whereby the free operation and movements of the wash-boards are permitted in whatever position they may be adjusted, as set forth.

2. In a washing machine, the combination, 35 with a tub and a shaft supported above the tub and provided with cranks, of laterally-adjustable frames in said tub, wash-boards sliding in ways in the said frames, blocks hung loosely on the cranks, blocks pivoted to the 40 wash-boards, and links pivoted to the said blocks, substantially as and for the purpose set forth.

3. In a washing-machine, the combination, 45 with the receptacle or body and the shaft with crank-arms supported above the receptacle or body, of the vertical carrying-frames *D D'*, suitably supported and adapted for a horizontal movement toward or away from the other, and provided with vertical ways *b*, the wash-boards *C C'*, provided with tongues playing in 50 said ways, and connecting-rods between said tongues and crank-arms, substantially as and for the purpose described.

4. In a washing-machine, the combination,

with the receptacle or body and the shaft with 55 crank-arms provided with the blocks *l l'*, supported above the receptacle or body, of the vertical carrying-frames *D D'*, adapted for a horizontal movement toward or away from the other, provided with vertical ways *b*, the wash-boards *C C'*, provided with tongues *a*, having the swiveling blocks *m m'*, and the links *k k'* between and pivoted to said blocks *l l'* and *m m'*, all substantially as and for the purpose described.

5. In a washing-machine, the combination, 60 with the receptacle or body and the shaft with crank-arms supported above the receptacle or body, of the vertical carrying-frames *D D'*, suitably supported and guided for horizontal 70 movements thereof toward and away from each other, provided with the friction-rollers *p*, the wash-boards *C C'*, suitably guided on said carrying-frames, and bearing upon said rollers and connecting-rods between said wash-boards 75 and crank-arms, substantially as and for the purpose described.

6. In a washing-machine, the combination, 80 with the receptacle or body having the apertured cleat *g*, and the shaft with crank-arms supported above the receptacle or body, of the vertical carrying-frames *D* and *D'*, the one *D'* having apertured horizontal arm *E'*, the removable pin *g'*, passing through apertures of 85 said arm and said cleat, and the carrying-frame *D*, suitably supported and guided for horizontal movements thereof toward and away from the frame *D*, the wash-boards *C C'*, vertically guided upon said carrying-frames, and connecting-rods between said wash-boards and 90 crank-arms, substantially as and for the purpose described.

7. In a washing-machine, the combination, 95 with the receptacle or body having the guiding-cleat *d*, and the shaft with crank-arms supported above the receptacle or body, of the vertical carrying-frames *D* and *D'*, having horizontal arms *E E'* running in suitable guides of said body, one of said frames provided with horizontal foot *d*, playing through said guiding-cleat, the wash-boards vertically guided upon said carrying-frames, and connecting-rods between said wash-boards and crank-arms, substantially as and for the purpose described.
